(57) **CLAIM**

I claim the ornamental design for a cap, as shown and described.

DESCRIPTION

FIG. 1 is a front view showing my new design for a cap and wherein the front view is identical to the right side view, the left side view is a mirror image of the right side view and the rear view is a mirror image of the front view of my new design;

FIG. 2 is a top view of my design shown in FIG. 1; and, FIG. 3 is a fragmentary cross-sectional view of the design of FIG. 1 taken at the top of the cap along line 3—3 of FIG. 1. The broken lines in FIG. 3 are for environmental purposes only and form no part of the claimed design. In addition, the cross-hatch pattern shown in FIG. 3 is generic in nature and does not limit the claimed invention to a specific material.
